UNITED STATES PATENT OFFICE.

ABRAHAM L. ENGLISH, OF EVERETT, WASHINGTON, ASSIGNOR OF ONE-EIGHTH TO W. J. BENNETT AND ONE-FOURTH TO J. HUNSAKER AND R. B. COLEMAN, ALL OF EVERETT, WASHINGTON.

SHINGLE-MACHINE.

No. 908,081.

Specification of Letters Patent.

Patented Dec. 29, 1908.

Application filed September 10, 1907. Serial No. 392,217.

To all whom it may concern:

Be it known that I, ABRAHAM L. ENGLISH, a citizen of the United States of America, and a resident of the city of Everett, in the 5 county of Snohomish and State of Washington, have invented certain new and useful Improvements in Shingle-Machines, of which the following is a specification.

The present invention relates to certain 10 new and useful improvements in horizontal shingle machines, aiming primarily to provide a machine of this type in which shingles can be cut in an efficient manner from a block carried on a reciprocating carriage.

15 With the above and other desirable objects in view, to be referred to as the description progresses, the invention resides in the features of construction, arrangement and combination of parts, hereinafter described 20 and succinctly defined in the annexed claims.

In the accompanying drawings, forming a part of this specification, and in which like reference numerals indicate like parts throughout the several views: Figure 1 is a 25 view in top plan of a shingle machine constructed in accordance with my invention, parts being broken away. Fig. 2 is a section taken on line 2—2 of Fig. 1. Fig. 3 is a plan view of the carriage removed, on large scale, 30 parts being shown in section, and Fig. 4 is a section taken on line 4—4 of Fig. 3.

Reference numeral 1 indicates the frame of the shingle machine, which as now considered, is provided with a stand 2 on which, 35 at opposite sides of frame 1, are journaled shafts 3. These shafts are provided with rollers 4, over which the band saw 5 passes.

6 indicates the carriage for feeding the bolt to the saw, said carriage being mounted for 40 reciprocation on suitable tracks 7, and being connected by a pitman 8 to the driving mechanism. This driving mechanism comprises a disk 9, fixed to a drive shaft 10, and provided with a pin 11 which rides in a slot 11', of an arm 12, pivoted at its lower portion, as at 13, to frame 1. Pitman 8 is guided between rollers 14, and is pivotally connected to the free end portion of arm 12 by a pin 15 which rides in a slot 15' of said 45 arm, as clearly illustrated in Figs. 1 and 2.

Carriage 6, on its sides, is provided with outwardly projecting frames 6', which embrace the tracks 7 so as to slidably support the carriage thereon, and in said frames 6' 50 are mounted suitable anti-friction rollers 6''

which engage the sides of said tracks 7, so as to reduce friction at these points, due to the slight twisting tendency of the carriage during the cutting operation. Tracks 7 are pivoted to frame 1, by approximately centrally arranged pins 16, and are normally tilted slightly from the horizontal to cause the carriage to travel in an inclined plane relatively to the line of cut of the saw, to effect clearance of the saw. 65

In the present machine, the carriage feeds the bolt to the saw for cutting in both directions, saw 5 being provided on each edge with teeth as clearly shown, and therefore tracks 7 are alternately tilted to relatively 70 reversely inclined positions. To effect this operation, I provide, on frame 1, horizontally disposed rock shafts, 17, arranged laterally of the tracks beneath the end portions thereof, of which shafts are provided with cams 18, 75 each engaged with the underface of the adjacent overlying track. Cranks 19, fixed to shafts 17, are connected by a link 20, whereby the said shafts are moved in unison to elevate the cams 18 of one shaft and lower the 80 cams of the other, thereby adjusting tracks 7. Shafts 17 are provided with laterally projecting parts 21 adapted to be engaged by arms 22, secured to carriage 6, to effect the rocking of said shafts. 85

Reference numeral 23 indicates the shingle bolt frame which is pivotally supported on carriage 6 on a pin 24, so that it can be swung to oblique positions relatively to the path of travel of the saw, as desired, whereby 90 the shingle bolt can be presented to the saw with one edge portion thereof foremost. This shingle bolt frame is swung to relatively reverse diagonal positions, by an arm 25 which is slidable in a bracket 27 of frame 95 1 and has lugs 26, 26' adapted to alternately strike said bracket and hold said arm while the carriage moves onward to the end of its stroke. The shingle bolt frame is held against accidental movement by suitable 100 means, as 28, in the form of a bar having its ends pointed and engaged, one in an aperture of a lug 29 on frame 23, and the other in an aperture of a spring metal plate 30, secured to carriage 6. Bar 28, is normally in 105 an inclined position as shown, and when the shingle bolt frame is swung from the position shown in Fig. 1, as when the work is to be fed into the other side of the saw, spring plate 30, upon being depressed by bar 28 per- 110

mits of the same being swung to a relatively reverse inclined position as indicated by dotted lines in fig. 1. The resistance offered by said spring plate is, however, sufficient to, 5 in conjunction with bar 28, hold the shingle bolt frame securely in position, when adjusted. Arm 25 is connected to the shingle bolt frame by a pin 25' which passes through a slot 31 in one side of carriage 6.

10 Shingle bolt frame 23, is provided with clamps 32, 32', preferably arranged at opposite sides thereof, the former as now considered, being fixed and the latter of which there are several, being yieldingly held in 15 operative position. Clamps 32' are arranged side by side with their roughened gripping portions 33 arranged well within the shingle bolt frame, while the shan's or bodies of said clamps are arranged in the side of said shingle bolt frame. At their inner ends, clamps 32' are cut out for reception of arms 34, formed with slots 35 in which pins 36, carried by the clamps, are received. Arms 34 are loosely mounted on a fixed shaft 37, and 20 are engaged by springs 38 held under tension to exert pressure to constantly tend to throw said arms forward, said springs being secured at one end to adjustable collars 39, and at their other ends to said arms. By this construction, clamps 32' being yieldingly pressed 25 outwardly, independent action thereof is permitted in compensating for unevenness in the side of the shingle bolt.

Reference numeral 40, indicates an equalizer bar, slidably mounted in the side of the shingle bolt frame at the outer side of shaft 37, and connected to clamps 32' by links 41. The connection, between said links and said clamps consisting of pins 42, riding in slots 35 of said links to allow for the independent movement of said clamps, as previously described.

Connected to equalizing bar 40, by links 44, are a pair of arms 45, pivoted at 46 to carriage 6 and projecting therefrom in opposite directions and formed with curved cam extensions which, as the carriage reaches the end of its travel, strikes rollers 47, carried by frame 1, and in moving by said rollers, said 50 curved cam extensions are forced inward, thereby drawing outward the equalizing bar 40 and the clamps 32' so as to release the shingle bolt to allow it to fall onto one of the underlying tables 48, 48' where it is set prior 55 to its being reclamped for travel with the carriage on its return stroke. Tables 48, 48' are of ordinary construction, comprising opposite sections hinged together by pins 49 and having at their free ends rests 50 for the 60 shingle bolt.

On the pins 49 are mounted sleeves 51 to which vertical supports 52 are fixed, said supports extending downwardly and engaged with suitable frame parts, whereby the re-

spective tables are secured in position. Ta- 65 ble 48 is secured in a laterally extending bar 53 of frame 1 while table 48' has its depend- 70 ing support slidably mounted in a suitable stand 54. I slidably support the said de- 75 pending support of this table to effect an ad- justment thereof in order that the shingle bolt can be properly positioned for a primary or trimming cut, such adjustment being effected by a lever 55 pivoted to said depend- 80 ent support and to the stand 54 and having its free end engaged with suitable teeth 56. After the trimming cut has been produced, 85 table 48' is reset to its normal position.

By feeding the shingle bolt to the saw in a diagonal position, as described, the cut is 80 started in the forward edge of the shingle bolt. Therefore the saw will cut across the grain of the wood, and the saw dust thus produced will readily break and fall from the cut, as contradistinguished from the clogging 85 action of the curled shavings, produced by a saw cutting with the grain of the wood, as found in machines where the saw is brought up against the forward face of the shingle bolt, thereby preventing burning of the saw. 90

Having thus fully described my invention, what I claim as new and desire to secure by Letters Patent of the United States, is:

1. In a machine of the character described, a frame, a carriage supported thereon for reciprocation, a saw for operating on the work conveyed during both strokes of said carriage, a shingle bolt frame supported on said carriage for movement to diagonal positions, and means for operating said shingle bolt frame to a relatively reverse diagonal position as the carriage reaches each end of its stroke.

2. In a machine of the character described, a frame, a carriage supported thereon for reciprocation, a saw for operating on the work conveyed during both strokes of the carriage, a shingle bolt frame swingingly supported on said carriage, means for holding said shingle bolt frame obliquely of the path of travel of the carriage, clamps on said shingle bolt frame, and means whereby said shingle bolt frame is swung to a relatively reverse position after a shingle has been cut, for the purpose specified.

3. In a machine of the character described, a frame, a carriage supported thereon for reciprocation, a double edged band saw for operating on the work as conveyed from each side thereof, a shingle bolt frame pivoted on said carriage, means connected to said shingle bolt frame provided with strike lugs, relatively fixed abutment means disposed to be engaged by the strike lugs of said means for swinging said shingle bolt frame to relatively 125 reverse diagonal positions, and means engaged with said shingle bolt frame for holding the same as swung.

4. In a machine of the character described, a frame, a saw for operating on the work, a carriage on said frame for feeding a shingle bolt to said saw, a shingle bolt frame supported on said carriage, clamps slidably supported in one of the side walls of said shingle bolt frame, a shaft supported on said shingle bolt frame, spring pressed arms on said shaft connected to said clamps for yieldingly pressing the same against the shingle bolt, and means for withdrawing all of said clamps simultaneously including a bar slidably supported on said shingle bolt frame, and link connections between said bar and said clamps.

5. In a machine of the character described, a frame, a saw for operating on the work, a carriage on said frame for feeding a shingle bolt to said saw, a shingle bolt frame on said carriage, clamps slidably supported in one of the sides of said shingle bolt frame, spring pressed rotatably supported arms connected to said clamps for yieldingly pressing the same against the shingle bolt, and means for withdrawing all of said clamps simultaneously including a bar slidably supported on said shingle bolt frame, and links connected

to said bar and having slotted connections with said clamps.

6. In a machine of the character described, a frame, a saw for operating on the work, a carriage on said frame for feeding a shingle bolt to said saw, a shingle bolt frame on said carriage, clamps slidably supported on said shingle bolt frame, a fixed shaft supported on said shingle bolt frame, arms rotatably mounted on said shaft and having slotted connection with said clamps, springs engaged with said arms for pressing said clamps against the shingle bolt, a slidably supported equalizer bar, links connected to said equalizer bar and to said clamps whereby upon sliding of said equalizer bar all of said clamps will be withdrawn to release the shingle bolt, and means on said carriage connected to said equalizer bar for operating the same.

Signed at Seattle, Washington, this 30th day of August, 1907.
